CLAIM

The ornamental design for a lighting fixture, as shown and described.

DESCRIPTION

FIG. 1 is a bottom plan view of a lighting fixture showing the new design;

FIG. 2 is a front elevational view thereof;

FIG. 3 is a back elevational view thereof.

FIG. 4 is a left side elevational view thereof;

FIG. 5 is a right side elevational view thereof; and,

FIG. 6 is a bottom perspective view thereof.

The broken lines shown on the drawings are understood to represent environmental structure that is not considered part of the claimed design.
